UNITED STATES PATENT OFFICE.

GUSTAV H. ZIMMER, OF BUFFALO, NEW YORK.

PUNCHING AND SHEARING MACHINE.

Application filed March 1, 1924. Serial No. 696,338.

My invention relates in general to punching and shearing machines, and in particular to that type of machine in which a block is inserted between a constantly reciprocating part and the punch or shear holder when the device is to be operated.

It will be understood that my invention is applicable to both punching and shearing machinery, but for clearness in this application, I will show and describe it as applied only to punching machines.

It is well known to those skilled in the art that in this type of machinery, it is very difficult to register the position of the work-piece with respect to the punch, since the punch is some distance away from the work-piece when it is started upon its downward movement.

The principal object of my invention has been to provide a device of this nature in which the punch may be moved by hand down to and in contact with the workpiece before the punch is operated, whereby it may be accurately registered therewith.

Furthermore, it has been an object to provide means whereby the reciprocating mechanism of the punch will be thrown into operation only after the punch has contacted with the work-piece.

Another object has been to provide a suitable retracting means whereby the punch and the plunger, which carries the same, may be brought back again to its normal vertical position.

Other objects have been to provide a device which shall be simple and safe to operate, and inexpensive to manufacture.

The above objects and advantages have been accomplished by the device shown in the accompanying drawings, of which:

Fig. 1 is a side elevation, partly in section, of my machine with portions thereof broken away.

Fig. 2 is a front elevation of the same.

Fig. 3 is a view similar to Fig. 1, and shows the parts in the position where the punch is being registered with the work-piece.

Fig. 4 is a similar view showing the parts in the position where the block has engaged the reciprocating link of the punch.

Fig. 5 is an enlarged fragmentary, sectional, view of the retracting mechanism.

In the drawings, 10 represents the housing of the punch, which is provided with the usual reciprocating link 11, which is op-

erated by the arm 12 of the punch. This arm is pivotally mounted at 13 and is shown in a fragmentary manner, since its connections and operating mechanism do not form a part of this invention, and furthermore, it is well known to those skilled in the art. It will be understood that the arm 12 is of the cam, eccentric, or crank driven type, which is constantly moving so as to cause a constant reciprocation of the link 11. Mounted within the body 10 is the usual plunger 14 of the punching machine to which the punch is attached. This plunger is provided with guides 18, which are mounted in suitable ways in the body 10 so that it will have a reciprocating movement. On the top of the plunger is mounted a block 15, which has on its upper side a concave surface 16. When this block is moved forwardly by means, to be hereinafter described, it will fill the space between the lower curved end 17 of the reciprocating link 11 and the plunger 14, whereby the plunger 14 will be actuated by the link.

Arranged at the side of the body 10 is an operating arm 20, which has near its central portion a U-shaped guide 21, which engages with a temporary pivot pin 22, carried by the body 10. The arm is provided with an operating handle 19. Arranged at the lower end of the arm is a weight 23, which keeps the arm normally upon the temporary pivot pin 22 and in the position shown in Fig. 1, and also serves to keep the plunger in its uppermost position. An auxiliary pivot pin 24 is arranged some distance from the temporary pivot pin 22, and, connected with it, is the upper end of a pivotal link 25. The lower end of the pivotal link is connected to a pin 26, which passes through a slot 27 in the body 10, and has its inner end secured in the guide 18. A similar pin 28 passes through a slot 29 and into the guide 18 on the opposite side of the machine, and it is provided with a weight (not shown) similar to the weight 23 for counter-balancing the plunger at that side of the machine.

Pivots mounted in the body 10 and arranged near the bottom thereof, and under the weight 23, is a shaft 30, having a lever 31 and a lever 32. The lever 32 is connected to the block 15 of the machine by means of a link 33. The lever 31 carries a pin 34, which is arranged to slide in a slot 35 formed in the end 36 of an operating link

37. The other end of the link is connected by means of a pivotal pin 38 to the operating arm 20.

Arranged preferably at the upper end of the guides 18 is a yoke 41 which carries the plunger retracting mechanism. This mechanism, shown enlarged in Fig. 5, comprises a housing 42, carried by the yoke 41 and provided with a cylindrical recess 43. A retracting plunger 45 is mounted in the housing 42, and is provided at its outer end with a flange 46, which fits into the recess 43. A helical spring 47 is mounted in the recess and beneath the flange 46, whereby the plunger is kept normally in the position shown in Figs. 1, 2, and 3. The retracting plunger 45 is provided with a recess 48 in which is mounted a helical spring 49 and a pressure plunger 50. The yoke 41 is provided with two downwardly extending arms 51 in which is pivotally mounted a plunger arm 52. The upper end 53 of this plunger arm is arranged to bear against the pressure plunger 50, and the lower end is provided with a square shoulder 54, which engages, when in its downward position with a fixed stop 55. The fixed stop is adjustable and carried by an arm 57 made preferably a part of the housing 10. The reciprocating link 11 is provided with a recess 56 with which the forward end of the retracting plunger 45 is engageable when the plunger is pushed inwardly and the recess is in an engageable position therewith.

35 The operation of the device will be apparent from Figs. 1, 2, and 3. When the operating arm 20 is in the position shown in Fig. 1, and during its movement to the position shown in Fig. 2, this arm will be supported by the temporary pivot pin 22. During this movement, the pivotal link 25, through the medium of the auxiliary pivot pin 24 and the pin 26 will move the plunger carrying the punch downwardly and in contact with the work-piece. While the operating arm is being moved from the position shown in Fig. 1 to the position shown in Fig. 3, the operating link 37 will be moved upwardly, and the pin 34 carried by the lever 31 carried by the shaft 30 will move without being operated upon through the slot 35 in the lower end 36 of the operating link. When, however, the parts have reached the position shown in Fig. 3, where the punch will be in contact with the work-piece, and the operating arm is further depressed, the pivotal connection thereof will be transferred from the temporary pivot pin 22 to the auxiliary pivot pin 24. When in this position the end of the slot 35 has been reached, and the operating link 37 is ready to operate upon the pin 34. As the operating arm 20 is moved to the position shown in Fig. 4, the levers 31 and 32 will be oscillated and the block 15 be forced in between the plunger

er 14 and the lower end 17 of the reciprocating link 11, whereupon the punch will be driven through the work-piece. When the operating arm is released, the weight 23 will serve to move the parts back to the positions shown in Fig. 1, and the pivotal connection will be transferred back to the temporary pivot pin 22 and the levers 31 and 32 will be returned to the position shown in Fig. 1.

As the plunger 14 is being moved downwardly, the yoke 41 carrying the plunger retracting mechanism is also moved downwardly, and when the parts have reached the positions shown in Fig. 4, the shoulder 54 at the lower end of the plunger arm 52 will come in contact with the fixed stop 55. When the parts are moved to the positions shown in Fig. 4, the plunger arm 52 will be moved inwardly so as to force the pressure plunger 50 into the recess 48 against the tension of the spring 49. This will move the retracting plunger 45 inwardly against the reciprocating link 11. When the block 15 is pushed inwardly and the plunger is moved downwardly by means of the link 11, the recess 56 in the link will be brought into engageable position with the forward end of the retracting plunger, and the same will be forced into the recess by means of the spring 49. When the link 11 is returned by its reciprocating mechanism, the weight of the parts will provide sufficient frictional contact between the end of the retracting plunger 45 and the recess 56 to keep the same engaged, even though the pressure upon the plunger 50 and spring 49 has been released by the upward movement of the plunger arm 52. When, however, the link has moved the plunger and its connected parts to their uppermost positions, the reversal of movement of the link will momentarily release the frictional contact of the retracting plunger with the recess of the link, and allow the spring 47 to withdraw the plunger 45 from the recess 56 in the link, thus allowing the plunger and its parts to remain in their uppermost positions while allowing the link to continue its reciprocation movement until the operating arm is again moved, as hereinbefore described.

Obviously some modifications of the details herein shown and described may be made without departing from the spirit of my invention, or the scope of the appended claims, and I do not, therefore, wish to be limited to the exact form herein shown and described, the form shown being merely a preferred form thereof.

Having thus described my invention, what I claim is:

1. In a punching machine, the combination with a reciprocating link, a plunger, and a movable block, of means for bringing the plunger into registering contact with the work-piece before the plunger operates

to punch such workpiece, and means for retracting the plunger engageable with the link.

2. A punch mechanism comprising means for bringing the plunger into registering contact with the work-piece before the plunger operates to punch such workpiece, including an operating arm, provided with two separate pivotal connections so arranged that the arm will be first pivoted only on one of the connections, and then only on the other of the connections.

3. In a punching machine, the combination with a reciprocating link, a plunger, and a movable block, of means for bringing the plunger into registering contact with the work-piece before the plunger operates to punch such workpiece, comprising an operating arm, two pivotal connections for separately and successively supporting the arm, and means connected with the operating arm for operating the movable block when the punch has been registered with the work-piece.

4. In a punching machine, the combination with a reciprocating link, a plunger, and a movable block, of means for bringing the plunger into registering contact with the work-piece before the plunger operates to punch such workpiece, comprising an operating arm, two pivotal connections for separately and successively supporting the arm, a bell crank lever, means connecting the bell crank lever with the movable block, slotted means connecting the operating arm with the bell crank lever, whereby the block will be moved in between the link and the plunger when the punch has been brought in contact with the work-piece.

5. In a punching machine, the combination with a body, a reciprocating link, a plunger, and a movable block, of means for bringing the plunger into registering contact with the work-piece before the plunger operates to punch such workpiece, comprising an operating arm, a temporary pivot pin for the arm carried by the body, an auxiliary pivot pin for the arm, means for connecting the auxiliary pivot pin with the plunger, and means connected with the operating arm for operating the movable block when the punch has been registered with the work-piece.

6. In a punching machine, the combination with a body, a reciprocating link, a plunger, and a movable block, of means for bringing the plunger into registering contact with the work-piece before the plunger operates to punch such workpiece, comprising an operating arm, a temporary pivot pin for the arm carried by the body, an auxiliary pivot pin for the arm, means for connecting the auxiliary pivot pin with the plunger, a bell crank lever, means connecting the bell crank lever with the movable block, slotted

means connecting the operating arm with the bell crank lever, whereby the block will be moved in between the link and the plunger when the punch has been brought in contact with the work-piece.

7. In a punching machine, the combination with a body, a reciprocating link, a plunger, and a movable block, of a plunger retracting means movable with the punch plunger and engageable with the link, whereby the plunger is automatically raised from the work-piece when the operation has been completed.

8. In a punching machine, the combination with a body, a reciprocating link, a plunger, and a movable block, of a plunger retracting means movable with the punch plunger, comprising a retracting plunger and engageable with the link, and means for actuating the retracting plunger when the punch plunger has reached the lower end of its travel.

9. In a punching machine, the combination with a body, a reciprocating link, a plunger, and a movable block, of a plunger retracting means movable with the punch plunger, comprising a retracting plunger engageable with the link, means for keeping the retracting plunger out of engagement with the link, and means for forcing the retracting plunger into engagement with the link when the punch plunger has reached the lower end of its travel.

10. In a punching machine, the combination with a body, a reciprocating link, a plunger, and a movable block, of a plunger retracting means movable with the punch plunger, comprising a retracting plunger, means for keeping the retracting plunger out of engagement with the link, a spring pressed pressure plunger mounted within the retracting plunger, a plunger arm movable with the punch plunger and in engagement with the pressure plunger, and a stop carried by the body with which the plunger arm is engageable when the punch has passed through the work-piece.

11. In a punching machine, the combination with a body, a reciprocating link, a plunger, and a movable block, of means for registering the work-piece before the plunger operates to punch the same, comprising an operating arm provided with two separate pivotal connections so arranged that the arm will be first pivoted only upon one connection, and then only upon the other connection, and a plunger retracting means movable with the punch plunger, whereby the plunger is automatically raised from the work-piece after the punching operation has been completed.

12. In a punching machine, the combination with a body, a reciprocating link, a plunger, and a movable block, of means for bringing the plunger into registering con-

tact with the work-piece before the plunger operates to punch such work-piece, comprising an operating arm provided with two separate pivoted connections so arranged that the arm will be first pivoted only upon one connection, and then only upon the other connection, and a plunger retracting means movable with the punch plunger, com-

prising a retracting plunger, and means for actuating the retracting plunger when the punch plunger has reached the lower end of its travel. 10

In testimony whereof, I have hereunto signed by name.

GUSTAV H. ZIMMER.
